UNITED STATES PATENT OFFICE.

CHARLIE B. HENDERSON, OF MOUNT VERNON, KENTUCKY.

ROLLING-PIN.

SPECIFICATION forming part of Letters Patent No. 670,779, dated March 26, 1901.

Application filed March 3, 1900. Serial No. 7,149. (No model.)

To all whom it may concern:

Be it known that I, CHARLIE B. HENDERSON, a citizen of the United States, residing at Mount Vernon, in the county of Rockcastle 5 and State of Kentucky, have invented certain new and useful Improvements in Rolling-Pins, of which the following is a specification.

My invention relates to improvements in 10 rolling-pins; and the object of my invention is the provision of a rolling-pin which will perform its function as a rolling-pin in a perfect manner and which will in addition be provided with compartments for containing soda, 15 baking-powder, &c., the rolling-pin being of simple, inexpensive, and durable construction, thus providing a very useful and practical article.

The invention consists of a rolling-pin embodying novel features of construction, combination, and arrangement of parts, substantially as disclosed herein.

Figure 1 represents a perspective view of 20 the rolling-pin, and Fig. 2 represents a vertical central sectional view thereof.

The body of my rolling-pin is made of wood or metal and is in the form of a hollow tube A, containing a division-wall B, dividing the body into two similar compartments C, the 25 purpose of which is to receive and contain, say, lemon and vanilla or for other purposes, as desired, and the ends of the body are provided with the interior threads D, with which engage the threaded stems E on the handles

F, which are formed with the shoulders G, 35 which abut snugly against the ends of the body and make a smooth joint, and the grasping portions of the handles are formed with cavities, recesses, or pockets H, provided with threads J to receive the screw caps or plugs 40 K, and these pockets are adapted to receive and contain such articles as baking-powder and soda or, in fact, any small article used in making bread or pastry.

The manner of using my rolling-pin being 45 obviously apparent, no description thereof is necessary; but it is evident that I provide a very useful, much-needed, and practical article for kitchen use.

I claim—

As an improved article of manufacture the rolling-pin herein described, consisting of the tubular body with central partition and threaded interiorly at the ends, hollow handles with threaded stems engaging the threads 55 of the body ends and having shoulders abutting snugly against the ends of the body to form smooth joints, and removable caps to the ends of the handles forming smooth joints therewith, all substantially as shown and described.

In testimony whereof I affix my signature in presence of two witnesses.

CHARLIE B. HENDERSON.
